UNITED STATES PATENT OFFICE.

ROBERT KNOX, OF MONTREAL, QUEBEC, CANADA.

STOCKING STRETCHER.

Application filed March 29, 1924. Serial No. 702,725.

This invention relates to forms for socks and stockings.

The object of the invention generally is the provision of a sock and stocking form, which is durable and efficient in use, and is readily and economically manufactured.

A more specific object of the invention is the provision of a form for giving socks and stockings a predetermined size.

Other objects of the invention will be in part obvious and will in part appear hereinafter.

The invention accordingly comprises the features of construction, combinations of elements, and arrangement of parts, which will be exemplified in the construction hereinafter set forth and the scope of the application of which will be indicated in the claims.

For a fuller understanding of the nature and objects of the invention reference should be had to the following detailed description taken in connection with the accompanying drawing, in which:

Figure 1 is a perspective view of a sock and stocking form constructed in accordance with this invention;

Fig. 2 is perspective view of the sock and stocking form assembled;

Fig. 3 is a side elevation of a sock and stocking form assembled in a sock.

Referring now to the drawing, 10 denotes a foot section shaped to conform generally to the outline of the human foot, thereby adapting it for insertion into the foot of a sock or stocking. A leg section 11 is provided in conjunction with the foot section 10, adapted to be detachably connected thereto and shaped for insertion in the leg of a sock or stocking. In constructing these sections a material such as wood is preferable since it will not damage the articles into which they are inserted and will give the sections sufficient strength to stand the strains to which they will be subjected.

With a view to providing for the detachable connection of the sections, one section is slotted or otherwise formed to receive the other section whereby the sections may be locked together. In this particular construction, the foot section 10 is provided with a T-shaped slot 12 located in the heel part and the leg section with a head 13 shaped for insertion through the slot 12. As will be observed, the head 13 is connected to the body of the leg section by a neck which may be turned in the slot 12 to effect the lock-

ing of the sections. When the sections are thus locked together, the connected ends of the sections extend beyond one another so that they will engage the sock or stocking, which cooperates to maintain the connection between the sections.

It will be readily understood that in constructing the sections, that they may be made of any desired size or form, so as to give a sock or stocking any predetermined size or shape. When the form is used for drying articles, it is inserted to prevent shrinkage, thereby maintaining the articles the desired size, but if the size of the article is to be increased, the form is inserted to stretch the article to the desired size.

With a view to adapting the form particularly to the drying of articles, a plurality of perforations 14 are provided in both sections, so that air may pass through the article positioned thereon. It will also be noted that the leg section 11 is provided with a hook 15, so that the form may be suspended from a support, either for purposes of drying the article mounted thereon, or for storing. In order to provide for suspending the form from an endless support such as a clothes line, the hook 15 is formed by cutting a curved notch 16 adapted to receive the support in the leg section. In this particular construction, the curved notch is cut in the upper end of the leg section, but it may be located in either side depending on the type of support on which it is to be mounted and the material from which the form is constructed.

One of the particular advantages of this form is the facility with which it may be inserted into and removed from socks and stockings. This results from the making of the form in two sections so that foot section may be inserted separately and properly disposed before the leg section is connected thereto.

In positioning the form in a sock 17, a simple method consists of drawing the leg portion of the sock over the foot portion and then inserting the foot section 10. After the foot section has been properly positioned, the head of the leg section is inserted through the slot 12 and turned through an angle of 90°, locking the head in engagement with the foot section. The leg portion of the sock is then drawn upward over the leg section 11. When the form has been inserted in the sock 17 as shown in Fig. 3,

- the connected ends of the sections engage the sock which cooperates to maintain the connection. Since the sections are loosely connected near the heel part, they swing apart under the influence of the weight of the foot section and the action of the sock when the form is suspended from a support. This moves the crossed ends away from one another so that the head of the leg section 5 forms an acute angle with the body of the foot section, and the sock tends to retain the head in this position making it difficult to turn the head through a sufficient angle to release it.
- 15 The removal of the form may be readily accomplished by setting the sections substantially at right angles to one another and then unlocking the leg section by rotating it through 90° . After the leg section has 20 been detached the foot section may be withdrawn.

Generally, difficulty is experienced in retaining the heel portions of socks the proper size, but with this type of form the crossed 25 ends at the heel part give the heel of the sock the required size.

Since certain changes may be made in the above construction and different embodiments of the invention could be made without departing from the scope thereof, it is 30 intended that all matter contained in the above description or shown in the accompanying drawing shall be interpreted as illustrative and not in a limiting sense.

35 It is also to be understood that the following claims are intended to cover all of the generic and specific features of the invention herein described, and all statements of the scope of the invention, which, as a 40 matter of language, might be said to fall therebetween.

Having described my invention, what I claim as new and desire to secure by Letters Patent, is:

45 1. A form adapted to give socks and the like a predetermined size and shape comprising in combination, a foot section and a leg section for insertion into a sock, one of said sections being adapted to receive 50 and engage the other section to effect de-

tachable connection of the sections, said sections having their engaging portions arranged to project and cooperate in stretching the heel portion of the sock.

2. A form adapted to give socks and the like a predetermined size and shape comprising in combination, a foot section and a leg section for insertion into a sock, one of said sections having an opening therein, the other section being provided with a head for insertion through said opening to detachably connect the sections, said sections having their engaging portions each arranged to project beyond the other and adapted to cooperate in stretching the heel portion 65 of the sock.

3. A form adapted to give socks and the like a predetermined size and shape comprising in combination, a foot section and an independent leg section having a head 70 adapted for locking engagement with said foot section and for insertion into a sock, the sock being engaged by the head and cooperating to maintain the locking connection.

4. A form adapted to give socks and the like a predetermined size and shape comprising in combination, a foot section and a leg section for insertion into a sock, said sections being adapted to be detachably 80 connected, the sections at the point of connection extending beyond one another presenting ends which engage the sock whereby said sock cooperates to maintain the connection.

85 5. A form adapted to give socks and the like a predetermined size and shape comprising in combination, a perforated foot section and a perforated leg section for insertion into socks and stockings, one of said sections having a slot, the other section being provided with a head for insertion through the slot to detachably connect the sections, the article being stretched cooperating to maintain the sections connected, 90 said leg section having a notch cut therein forming a hook for suspending the form from a support.

In testimony whereof I affix my signature.
ROBERT KNOX.
